(57) **CLAIM**

(21) Appl. No.: **29/172,265**

We claim the ornamental design for a telescoping ladder leg extender having mated toothed elements and self-leveling foot for uneven terrain, as shown and described.

(22) Filed: **Dec. 10, 2002**

DESCRIPTION

(51) LOC (7) Cl. **25-04**

FIG. 1 is a perspective view of a telescoping ladder leg extender having mated toothed elements and self-leveling foot for uneven terrain showing our new design;

(52) U.S. Cl. **D25/68**

FIG. 2 is a front elevational view thereof, the rear elevational view being a mirror image thereof;

(58) Field of Search 182/107, 108, 182/109; D25/68

FIG. 3 is a left side elevational view thereof;

(56) **References Cited**

FIG. 4 is a right side elevational view thereof;

U.S. PATENT DOCUMENTS

FIG. 5 is a top plan view thereof;

FIG. 6 is a bottom plan view thereof; and,
